UNITED STATES PATENT OFFICE

163,038

CAKE OF SOAP

Edward F. Haskell, New York, N. Y.

Application July 23, 1946, Serial No. 131,864

Term of patent 14 years

(Cl. D73—1)

To all whom it may concern:

Be it known that I, Edward F. Haskell, a citizen of the United States, residing in city, county, and State of New York, have invented a new, original, and ornamental Design for a Cake of Soap, of which the following is a specification, reference being had to the accompanying drawings, forming part thereof.

Fig. 1 is a plan view of a cake of soap showing my new design.

Fig. 2 is a side elevational view thereof, and
Fig. 3 is an end elevational view thereof.

I claim:

The ornamental design for a cake of soap, as shown.

EDWARD F. HASKELL.
